Application July 3, 1943, Serial No. 493,376

2 Claims. (Cl. 2—42)

This invention relates to brassières, and more particularly to a brassière adapted to support and shape the breasts to desired conformation.

In our Patent No. 2,317,664, dated April 27, 1943, is shown a brassière having some of the features of the present invention. In said patented brassière is shown adjustable breast openings covered at the front by adjustable flaps which are movable to lowered position to expose the breasts through the openings, for nursing purposes. The present brassière is not of the nursing type, and while incorporating the breast openings constructed as shown and described in the above mentioned patent, it does not employ the movable and adjustable flaps thereover. Instead it provides fixed and immovable cup-shaped outer coverings or front panels over the breast openings so that the breasts accommodated therein and held in conformity therewith, will be encompassed by said coverings and covered and supported thereby.

In a brassière of this character is therefore provided the combination of an adjustable breast-conforming opening with a non-adjustable permanently-shaped covering member, and through this combination of elements, a comfortable accommodation of the breasts is attained with the desirable moulding characteristics usually sought in garments of this character.

More particularly, the invention contemplates the provision of a brassière having breast openings which are extensible because of overlapped parts of the garment disposed around the same, and which are covered by an outer covering of fixed shape and size and which is non-adjustable.

In the accompanying drawing forming a part hereof, Fig. 1 is a front elevation of a brassière constructed in accordance with the invention; Fig. 2 is a view of the inner side of the brassière; Fig. 3 is a sectional view through one of the breast-supporting portions of the brassière, and Fig. 4 is a modified elastic insert located between the breast supports.

With reference to the structure shown in Figs. 1 to 3, inclusive, the body portion of the garment is composed of the two main inner sections 1 and 2 adapted to be detachably united at the rear, when the garment is in position of wear, by means of the hooks 3 secured at the end of the elastic webbing 4 on section 2, which are selectively engaged with one pair of the eyelets 5 on the tab portion 6 located at the end of the portion 1. At the front of the garment, the sections 1 and 2 are connected at the lower part by elastic webbing 7 which is extensible longitudinally

of the garment, but not transversely thereof. Above the elastic insert, the two body portions 1 and 2 are connected by the open-mesh inelastic insert 8. A variation of this arrangement is shown in Fig. 4, wherein an inverted V-section 9 of elastic webbing extends for the full width of the garment between the breast-receiving parts.

Each of the body portions 1 and 2 includes 10 an orificed cupped insert 10, having a breast orifice 11, the edge of said opening being suitably reinforced by the binding 12. It will be noted that the material of each of the cupped sections 10 is overlapped, as indicated at 13 and 14, said overlapping occurring below each orifice so that these overlapped portions are located between the orifice and an arcuately curved reinforcing strip 15 extending around the marginal edge of the insert 10 from the point 16 near the central line of the garment to the point 17.

The result of this construction is to cause the body portions 1 and 2 and particularly the breast sections 10 surrounding the orifices 11 to assume a cupped or frusto-conical conformation, as clearly shown in Fig. 3, and since the material of these sections around the orifices is overlapped and unsecured adjacent to the marginal edges of the orifices, expansion of the orifices under breast pressure, without material 25 change in the shape of the orifices, is attained.

Each of the body portions 1 and 2 is provided with cupped outer covering panels 19 and 20, shaped to conform to the shape of the portions 10 and extending over and covering the same. These 35 outer covering panels 19 and 20 may be constructed in any suitable manner, such as for example, having the lower portions of closely-woven fabric, as indicated at 21, and the upper part of mesh or lace-work, as indicated at 22. 40 These cover panels are formed of segmental sections stitched together resulting in a permanently cupped formation, serving in co-operation with the orificed parts 10 to both support the busts and to provide moulding conformation thereof. The 45 manner in which the permanently attached cover members 19 and 20 extend over the orificed members 10 will be clearly seen in Fig. 3, and it will be clear from the same that while the orificed elements 10 tend to shape or cone the breasts, the 50 fixed and non-expansile outer covering panels limit marked breast protrusion and thus act as a restraining influence as well as a support.

The garment is supported from the shoulders in the conventional manner, by the shoulder 55 straps 25, secured at 26 to the body portions 1 and

2, respectively. Each strap 25 is looped through the ring 27 and is adjustable as to effective length therethrough by the buckle 28. The ring 27 extends through the fabric loop 29 secured to the top edge of the garment over each breast supporting section.

Through the arrangement disclosed, co-operative action between the orificed breast portions of the garment and a fixed, outer covering panel is attained, whereby the inner orificed sections effectively shape the breasts as desired, while the outer coverings provide a supporting and restraining action.

Having described several embodiments of the invention, it is obvious that the same is not to be 15 restricted thereto but is broad enough to cover all structures coming within the scope of the annexed claims.

What we claim is:

1. In a brassière, a body portion having a breast-covering area provided with an inner breast section formed with a breast orifice, said inner section having overlapped parts permitting distension of said orifice under breast pressure, said inner section being surrounded by an arcuate binding member having one end located at the upper edge of the garment slightly to one side of the vertical center line thereof and curving downwardly and around the inner breast section and extending upwardly to the top edge of the garment, the lowermost part of said arcuate binding member being located well above the

lower edge of the garment and a fixed cupped cover member overlying the inner orificed member and permanently and non-removably extending thereover, the binding member extending 5 around the edge and defining the shape of said cover member and holding the overlapped parts of the inner section in overlapped relation.

2. In a brassière, a body portion having a breast-covering area provided with an inner breast section formed with a breast opening, said inner breast section being surrounded by an arcuate seaming reinforcement having one end located at the upper edge of the garment adjacent to the vertical center line thereof, said seaming reinforcement extending downwardly on a curved line and thence upwardly to reach and have its other end terminate at the upper edge of the garment remote from the center thereof, the lowermost extension of said reinforcement being spaced above and away from the lower edge of the garment, said orificed inner breast section having unsecured overlapped parts maintained in overlapped relation well above the lower edge of the garment by said arcuate seaming reinforcement, and a fixed cupped outer covering member having its lower edge engaged in and maintained by said arcuate reinforcement, said cupped outer member overlying the orificed inner breast section and constituting a non-adjustable, permanently shaped outer covering member.
